John A. Sakaley, Jr., 4313 Wheeler Road SE., Apt. 101,
Washington, D.C.

Filed July 11, 1962, Ser. No. 70,891

Term of patent 14 years

(Cl. D65—1)

(Granted under Title 35, U.S. Code (1952), sec. 266)

FIG. 1 is a perspective view of the front and one side of a vacuum pump for desoldering device, showing my new design;

FIG. 2 is a top plan view thereof, with the cover element removed for convenience of illustration;

FIG. 3 is a front elevational view thereof, and

FIG. 4 is a cross-sectional view thereof, taken on the line 4-4 of FIG. 3.

The rear and opposite side of the article are mirror images of the front and side, respectively, shown in FIG. 1.

The invention shown herein may be manufactured and

used by or for the Government for governmental purposes without the payment of any royalty thereon.

I claim:

The ornamental design for a vacuum pump for desoldering device, substantially as shown and described.
